(57) **CLAIM**

We claim the ornamental design for a connector for landing rails, as shown and described.

DESCRIPTION

FIG. 1 is a perspective view of connector for landing rails showing our new design;

FIG. 2 is a first side elevational view thereof;

FIG. 3 is a second side elevational view thereof;

FIG. 4 is a bottom plan view thereof;

FIG. 5 is a top plan view thereof; and,

FIG. 6 is an exploded view from the first side thereof.
